J. & F. C. KUNZ.
EGG TURNING TRAY FOR INCUBATORS.
APPLICATION FILED DEC. 20, 1906.

977,638.

Patented Dec. 6, 1919.

UNITED STATES PATENT OFFICE.

JOHN KUNZ AND FREDRICK, C. KUNZ, OF MIDDLETOWN, OHIO.

EGG-TURNING TRAY FOR INCUBATORS.

977,638.

Specification of Letters Patent. Patented Dec. 6, 1910.

Application filed December 20, 1906. Serial No. 348,672.

To all whom it may concern:

Be it known that we, JOHN KUNZ and FREDRICK C. KUNZ, citizens of the United States, residing at Middletown, in the county of Butler and State of Ohio, have invented certain new and useful Improvements in Egg-Turning Trays for Incubators; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in egg trays or turners for incubators.

The object of the invention is to provide such a device having a capacity for turning in a body different sizes of eggs so that the eggs shall be substantially uniformly presented to the action of the temperature of the incubator.

Preceding a detailed description of the invention, reference is made to the accompanying drawings, of which—

Figure 1, is a top plan view of the egg tray with parts broken away. Fig. 2, is a horizontal side elevation thereof. Fig. 3, is a horizontal section on the line *i i* of Fig. 1. Fig. 4, is an enlarged view of the dial by means of which the extent of rotation of the rollers is determined. Fig. 5, is a detail view of the gage by means of which the rollers are selected. Fig. 6, is a sectional view of one side of the device on the line *t t* of Fig. 1. Fig. 7, is an end view of a corner of the tray.

In a detail description of the invention, similar reference characters indicate corresponding parts.

The supporting frame consists of side and end strips 1 united at their ends by bottom brace strips 2 which tie the side and end pieces of the frame together. On one side of the frame there is a longitudinal strip 3 which supports the journals of the rollers 4 on one side of the frame, said journals being also supported in the side strip 1 at that side of the frame. The journals of the other ends of the rollers are dropped into openings in the other side strip 1. This may be done whenever it is necessary to change the rollers to suit different sizes of eggs. It will be understood, however, that all the eggs sup-

ported between each pair of rollers of approximately the same size, should also be of approximately the same size. When it becomes necessary to place rollers of different sizes in the tray, owing to the different sizes of eggs, it is necessary that the eggs supported on a roller of smaller diameter which is adjacent to one of larger diameter, be prevented from coming in contact with the larger roller. This is accomplished by placing a rod 5 parallel with and adjacent to said larger roller, as seen in Fig. 1. This rod 5 has its ends bent and inserted in any two of the openings 6 arranged in the upper surface of the side strips 1, and it may be removed to any point where its use may be required.

The bottom of the tray is inclosed by a wire screen 7, the purpose of which is to catch the chickens as they are liberated from the eggs through the action of the incubator. The eggs-supporting rollers have sprocket wheels 8 on their ends which are of uniform diameter, and around these sprocket wheels passes an endless chain 9, a common means for rotating the rollers in a body. In order to maintain the lower run of the chain in proper engagement with the sprocket wheels, a slide 10 is provided which is inserted at one end of the tray along the bottom strip 2, and beneath the chain. See Figs. 3 and 7. Whenever it becomes necessary to remove one or more rollers to be replaced by other rollers of different size or sizes, the strip 10 may be removed by drawing it through the opening 11 at one end of the tray. The opening 11 is closed by a door 24, and the slide or strip 10 is thus prevented from moving out of its position below the chain while the tray is in use. The roller at one extreme end of the tray has its journal made square and extended through the side of the frame as at 12, such square end being adapted to receive a key (not shown) by means of which said roller may be rotated and therewith the other rollers through the chain 9. Fitting over said extended journal is an indicator in the form of a dial 13 which is fixed in its position and bears a zero mark.

18 designates a pointer which is fixed to the end 12 of the roller and is movable over the face of the dial to and from the zero mark when a complete rotation of the rollers is made.

14 designates a rotatable piece containing a sight opening 15 through which the figures

on the inner or outer concentric row of the dial 13 are visible. This sight piece 14 is utilized in connection with the inner or outer row of figures as presently described. The 5 pointer 18 is started from the zero point in the outer row of figures.

17 is a frame-work secured against a side of the tray and serving to maintain the piece 14 in suitable position, said piece 14 having 10 an elongated opening 16 which permits it to be elevated or lowered to bring the sight opening 15 in line with the outer or inner figures on the dial.

In Fig. 5 is shown a gage by means of 15 which the eggs are sized and the rollers selected. This gage is suitable for the usual sizes of hen eggs, which are indicated by the six numbers, 14, 15, 16, 17, 18 and 19. For 20 these sizes of eggs, it is found that, only two sizes of rollers are necessary, which are represented by the numerals 1 and 2. The roller 1 is for the smaller eggs 14, 15 and 16, and the large roller 2 is for the larger eggs 17, 18 and 19. It is not necessary to provide a 25 roller for each size of eggs, as the eggs need only be given an approximately half turn. The device is operated as follows: The operator first rotates the pointer 18 until it is 30 opposite the zero mark on the dial 13. He then selects the largest egg from among the lot which it is desired to incubate, and ascertains its gage number and the size of roller corresponding to that number, by means of 35 the gage shown in Fig. 5. If the egg gages 19, the larger rollers are selected and placed in the frame and the egg placed in contact therewith. The sight piece 14 is then brought opposite the numeral 19 on the dial 13. This indicates the extent of rotation to 40 be given the rollers, whether large or small, to give all the eggs that may be placed in contact with the rollers, an approximately half turn. The gage size of the remainder of the eggs is then ascertained. Eggs gaging 45 14, 15 or 16 are placed in contact with the small rollers, and eggs gaging 17, 18 or 19 are placed in contact with the large rollers. This operation is continued until all the eggs are gaged or the tray is full. When 50 it is desired to turn the eggs, the square shaft 12 is rotated to the extent of 19 points on the dial 13, by means of the key. In other

words, the pointer 18 is rotated from the zero mark to 16 and then to 19 indicated by the sight piece 14 which was previously set. 55 This gives the rollers a 1 and $\frac{4}{5}$ ths turn and is sufficient to give all the eggs, whether large or small, an approximately half turn. It will be understood that the sight piece 14 is set only once for each tray of eggs, and the 60 extent of movement given all the eggs is controlled by the first large egg.

We claim:

1. In an egg-turning tray for incubators, a suitable frame, a series of removable egg-supporting rollers having sprocket wheels thereon, a driving chain for said rollers engaging said sprocket wheels on the ends of said rollers, and a removable bar below the sprocket chain to maintain it in proper engagement with the wheels. 65

2. In an egg tray or turner, the combination with a frame, of a series of removable rollers mounted therein, a pointer rigidly attached to one of said rollers, means comprising a series of sprocket wheels attached to said rollers, a chain extending from the roller having the pointer to the sprocket wheels of the remaining rollers, means comprising a dial co-operating with said pointer, 70 and a sight bar movable over said dial to indicate the extent of movement to be given the roller having the pointer. 75

3. In an egg tray or turner, the combination with a frame, of a series of removable 80 rollers mounted therein, said rollers being of different sizes, a pointer rigidly attached to one of the larger size rollers, means comprising a series of uniform sprocket wheels attached to said rollers, a chain extending 85 from the roller having the pointer to the sprocket wheels of the remaining rollers, means comprising a dial co-operating with said pointer, and a bar having a sight opening therein movable over the face of said 90 dial to indicate the extent of movement to be given the roller having the pointer. 95

In testimony whereof we affix our signatures, in presence of two witnesses.
